METHOD AND APPARATUS FOR MAKING
WALLBOARD

William G. Brubacher, Montreal, Quebec, Canada

Application February 11, 1942, Serial No. 430,422

12 Claims. (Cl. 92—39)

This invention relates to a method and apparatus for making wall board and the like.

Wall board has been made for many years with fibrous material of different types, for example, from wood fiber, sugar cane fiber, etc. Boards of this type possess a very low degree of structural strength and may be surfaced only at substantial expense and with difficulty. The reason for this is that the material from which the board is made is distributed throughout the body of the board with almost perfect uniformity, as the result of which both surfaces of the board contain a substantial proportion of relatively long coarse fibers, thus making it difficult to provide the board with a smooth surface.

An important object of the present invention is to provide a novel method of making wall board from fibrous material wherein the finished board has the portion adjacent one surface thereof formed entirely of very short fibers, thus rendering such surface of the board quite smooth without the necessity for performing additional operations thereon.

A further object is to provide a method wherein in the portion of the board adjacent the opposite surface is made up very largely of interlocked relatively long coarse fibers with a very small proportion of shorter fibers therein, whereby the resultant board possesses substantially greater structural strength than boards made of similar materials of equal volume produced in accordance with prior methods.

A further object is to provide a method of making wall board of the character referred to wherein in the method operates continuously to provide a finished board structure having openings therethrough whereby the finished board is materially thicker than boards produced with prior methods and containing the same amount of material, and wherein the finished board possesses an unusually high degree of heat insulating value.

A further object is to provide a novel type of apparatus for producing wall board of the character referred to, wherein the apparatus operates continuously to produce the board.

A further object is to provide novel means for feeding the fiber-containing pulp to the inlet end of the apparatus in such a manner as to automatically control the distribution of fibers in the resultant board so that one side of the board contains largely long coarse fibers while the other side of the board is made up entirely of short fibers to produce a smooth face at such side of the board.

A further object is to provide novel means in

5 the apparatus for continuously producing a wall board having openings of substantial size extending through the length of the board to increase the insulating value of the board and to produce a board of greater thickness with the same volume of material per unit of length and width.

10 A further object is to provide an apparatus of the character referred to wherein the elements which form the openings through the length of the board are positively supported at one end, and have their opposite end portions supported by the material of the board itself during formation thereof, the forming of the bottom portion of the board with longer coarser fibers rendering more efficient the supporting in such manner of the elements which form the openings.

15 A further object is to provide novel means in association with the board forming mechanism for effecting a separation of the fibers and the distribution of the fibers to the board forming mechanism in such a manner that the top portion of the board will be made up wholly of material containing short fibers whereas the bottom of the board, beneath the opening forming elements, will be made up largely of longer coarser fibers.

20 Other objects and advantages of the invention will become apparent during the course of the following description.

25 In the drawings I have shown one form of apparatus particularly adapted for practicing the method. In this showing—

30 Figure 1 is a side elevation of the apparatus,
35 Figure 2 is a central vertical longitudinal sectional view through the apparatus,
Figure 3 is a transverse vertical sectional view on line 3—3 of Figure 1,

40 Figure 4 is a similar view on line 4—4 of Figure 1,
Figure 5 is an enlarged detail perspective view of one of the forming tubes, a portion being broken away,

45 Figure 6 is an enlarged transverse sectional view on line 6—6 of Figure 5,
Figure 7 is an enlarged fragmentary detail sectional view of one of the deckel supporting pulleys and associated elements, parts being shown in elevation,

50 Figure 8 is a section on line 8—8 of Figure 7,
Figure 9 is a detail perspective of a portion of a wall board produced in accordance with the present invention, and,
Figure 10 is a sectional view through a portion

of a wall showing the wall board attached thereto.

Referring to the drawings it will be noted that the present apparatus is generally similar in construction to a conventional Fourdrinier paper machine, although the apparatus has been altered and additions have been made thereto which makes it, in effect, a different apparatus adapted to make the novel wall board in accordance with the present invention, which cannot be done on a conventional Fourdrinier machine. The apparatus may be provided with two main supporting frames 10 and 11 respectively comprising side frame members 12 (Figure 4) and 13 (Figure 3) and between the side frame members are rotatably supported a series of table rolls 14 over which passes the upper run 15 of an endless wire indicated as a whole by the numeral 16. At the forward end of the apparatus the wire passes around a breast roll 17, while at the rear or outlet end of the apparatus the wire passes around a couch roll 18. The lower run 19 of the wire passes beneath a stretch roll 20 and over a guide roll 21, as shown in Figures 1 and 2. The stretch roll 20 is supported for rotation by upstanding members 22 which may be formed integral with the side frame members 13 and the stretch roll may be vertically adjusted by rotation of screws 23 connected to the bearings 24 of the stretch roll. The guide roll 21 may be supported by depending bracket arms 25 carried by the side frame members 12, and the guide roll is longitudinally adjustable by screws 26 connected to the bearings 27 of the guide roll. The adjusting means for the rolls 20 and 21 are conventional and form no part per se of the present invention.

Between the breast roll 17 and the first table roll 14 the apparatus is provided with a pair of suction boxes 28 the surfaces of the top edges of which are arranged in a common plane with the upper limits of the breast roll 17 and table rolls 14 so that the upper run 15 of the wire passes directly over these suction boxes so that a substantial amount of water will be constantly taken from the pulp mass through the wire in a manner to be described. Each suction box 28 is provided with a downwardly extending drain pipe 29 controlled by a valve 30, and the lower ends of the pipes are connected with a drain trough 31, or with suitable conventional suction creating means, depending upon whether it is desired to permit water to drain by gravity from the mass passing over the boxes 28, or to induce a drainage of water from the mass. The trough 31 may be arranged in a pit 32 suitably connected with a sewer.

The last table roll 14 toward the outlet end of the apparatus that is, the right hand end as viewed in Figure 2, serves as a squeeze roll in a manner to be described, and is separated from the next table roll 14 to provide a space for a plurality of suction boxes 33 each of which is provided with a drain pipe 34 leading to a manifold pipe 35 (Figure 1), and the latter pipe may be suitably connected in the usual manner to suction creating means similar to that employed for a conventional Fourdrinier machine. Each pipe 34 may be controlled by a valve 36.

It will become apparent that the watery pulp mass is fed to the top wire in a novel manner quite distinct from the methods employed with a Fourdrinier machine. Referring to Figure 2 the numeral 37 designates a control box having one end wall 38 and the two side walls 39 having

their lower edges in a common plane substantially contacting the top run 15 of the wire, and a partial bottom wall 40 (Figure 2) extends from the wall 38 to a point adjacent the beginning of the top run 15 of the wire. The other end wall 41 of the control box has its lower portion curved outwardly from the box as at 42 (Figure 2) and terminating a substantial distance above the top run 15 of the wire. The distance between the lower extremity of the wall 41 and the top run 15 of the wire determines the thickness of the feed of the mass to the wire, as will become apparent.

Spaced walls 43 and 44 extend transversely across the box 37 to divide the latter into three compartments 45, 46 and 47, for a purpose to be described. The lower edges of the partitions 43 and 44 terminate a substantial distance above the top run 15 of the wire as clearly shown in Figure 2. The feeding of material into the compartments 45, 46 and 47 is determined by the operation of a pulp screen indicated as a whole by the numeral 48. This screen is provided with upstanding imperforate walls 49 to the bottom of which is connected a screen element 50 having slots cut therethrough for the passage of the pulp. The slits 51 in the screen 50 over the compartment 47 are of such size as to permit only the smallest shortest fibers to pass therethrough while the slits 52 over the compartment 46 are of such size as to permit fibers up to a medium size to pass into the compartment 46. The slits 53 over the compartment 45 are of such size as to permit the passage therethrough of any fibers up to the largest size. It will be apparent, therefore, that the finest fibers can pass through any portions of the screen; that nothing larger than medium sized fibers can pass through the slits 52; and that any of the fibers can pass through the slits 53. Since the largest fibers can pass solely through the slits 53 it will be apparent that the fibers passing into the compartment 45 will be predominantly the largest coarsest fibers. Similarly, only medium and fine fibers can pass into the compartment 46, while only the finest fibers can pass into the compartment 47. This control of fiber size is important in the production of the wall board contemplated by the present invention.

The screen 48 is suspended by spring steel elements 54 connected at their upper ends to supporting elements 55 carried by an overhead support 56. While it is not necessary to vibrate the screen 48, such operation is preferred and for this reason a constantly driven shaft 57 is provided with an eccentric 58 operating in a strap 59. The latter element is connected by an arm 60 to a pivot pin 61 carried by the adjacent wall of the screen 48 and accordingly it will be apparent that the screen is constantly vibrating during the operation of the apparatus. Pulp may be fed to the screen in any suitable manner, for example, from a stock inlet hopper 62, and the watery pulp mass in the screen 48 may be kept thoroughly agitated by a stream of water flowing thereinto through a nozzle 63.

The stock is fed to the top run 15 of the wire very much thicker than is true in a conventional Fourdrinier machine, and it will be obvious that a conventional deckel strap employed for confining the pulp mass on the wire cannot be employed with the present invention. In Figures 1, 7 and 8 I have illustrated a novel type of deckel which is particularly adapted for use with the present apparatus. Vertical pulleys 64, 65 and

66 (the latter of which is shown in detail in Figures 7 and 8) are supported on shafts 67 rotatable in bearings carried by depressed supporting frame elements 68 forming portions of the opposite frame members 12. A suitable form of bearing for each of the shafts 67 (except as will be referred to) is shown in Figure 7. Each pulley may have at its lower end a hub 69 fixed to the associated shaft by a set screw 70 and the lower end of the shaft is mounted in a bearing 71 and supported by a thrust bearing 72. The bearing so far described is all that is necessary for the shafts of the pulleys 64 and 65, the set screws 70 providing for vertical adjustment of each associated pulley 64 or 65, which is the only adjustment necessary for such pulleys. The bearing for the shaft of the pulley 66 is preferably provided with horizontal take-up means in which case the bearing 71 is provided with a flange 73 slidable in guides 74. The end of the flange 73 remote from the other pulleys is provided with an upstanding lug 75 received between collars 76 secured to an adjusting screw 77 provided with a head 78 and threaded through a lug 79 carried by the corresponding supporting frame element 68.

A deckel unit indicated as a whole by the numeral 80 passes around the pulleys 64, 65 and 66 and each of the pulleys is provided at its ends with outstanding flanges 81 so as to properly vertically position the deckel unit for a reason which will become apparent. The deckel unit comprises a flexible belt 82 preferably perforated as at 83 and a screen 84 (Figure 8) is coextensive with and secured against the outer face of the belt 82. Each of the deckel supporting pulleys is arranged in close proximity to the adjacent edge of the top run 15 of the screen 16, as shown in Figure 8. The lower flange 81 of each pulley is disposed just below the adjacent edge of the top run 15 of the screen and the lower edge of the belt 82 obviously will be supported on the lower flanges 81 of the pulleys. The face of the inner run of the belt 82 adjacent the edge of the screen 15 will barely clear the screen, and accordingly the lower edge of the deckel screen 84 will overlie the adjacent edge of the top run of the screen 16. This arrangement is shown in Figure 8. The deckel arrangement adequately confines the thick mass of pulp upon the top run of the screen 16 and assists in draining water therefrom, due to the use of the screen 84 and perforated belt 82, while at the same time the deckel arrangement does not interfere with or cause wear upon the screen 16. It will be obvious that one of the deckel units is arranged at each side of the apparatus, as will be clear from Figures 3 and 4.

The deckel pulleys 63 and 64 are positively driven by the means shown in Figures 1, 2, 4, 7 and 8. At each side of the apparatus is arranged a pair of bearings 86 and 87 the former of which is arranged adjacent the corresponding pulley 66 between opposite runs of the belt 82. The bearing 87 may be arranged to the left, as viewed in Figure 1, of the corresponding pulley 64, and both bearings may be supported by suitable portions of the side frame members 12. A shaft 88 is rotatably supported in the bearings 86 and 87 at each side of the apparatus and carries bevel gears 89 and 90 respectively meshing with bevel gears 91 and 92 carried by the upper ends of the shafts 67 of the respective pulleys 64 and 66. Each bevel gear 90 is splined as at 93 on the shaft 88 so as to slide on the shaft in accordance with horizontal adjustments of the associated pulleys 66.

Each bevel gear 90 is maintained in mesh with its associated gear 92 by a bearing bracket 94 having its ends respectively surrounding the shaft 88 and the shaft 67 of the associated pulleys 66 (Figure 7).

Adjacent the inlet end of the apparatus is arranged a supporting frame structure indicated as a whole by the numeral 95 and extending transversely of the apparatus. This frame structure carries a pair of upstanding bearings 96, one for each of the shafts 88. Each of these shafts carries a pulley 97 around which passes a belt 98. The upper end of each belt 98 passes around a pulley 99 mounted on an overhead drive shaft 100 as shown in Figures 1 and 2. The shaft 100 carries a pulley 101 around which passes a drive belt 102 and this belt drives a pulley 103 on the drive shaft 57 for the eccentric 58. The latter shaft may be supported in any suitable manner, for example, on the upper end of a frame 104.

The wall board is continuously formed on the upper run 15 of the wire 16, as will become apparent, and in the formation of the board, openings are formed extending longitudinally of the board. For the purpose of forming these openings a plurality of tubular formers, each indicated by the numeral 105, is employed. One of the tubes is shown in detail in Figures 5 and 6 and one of the tubes is shown in position in Figure 2 in the wall board being formed with the apparatus. Each tube 105 is of uniform cross-sectional size throughout its length and is spirally grooved as at 106 for a purpose to be described. Each tube is preferably provided with a number of radial openings 107 the purpose of which also will be described later. At its left hand end as viewed in Figures 2 and 5, each tube 105 is provided with a pulley 108 around which passes a driving belt 109 and these belts are driven from a shaft 110 by one or more pulleys 111. In other words, a separate pulley may be mounted on the shaft 110 for each of the belts 109 or a single elongated pulley may be employed, as will be obvious. One end of the shaft 110 is provided with a driving pulley 112 which may be driven from any suitable source of power.

Each of the tubes 105 is supported in a bearing 113 (Figure 2) carried by the wall 38 of the box 37 (Figure 2) and outwardly of such box 50 each tube is also supported in a bearing 114 carried by the supporting structure 95. It will be apparent that from its bearing 113 (Figure 2) to its extreme right hand end each tube is entirely free, there being no bearings to support the tube 55 other than those described. In the operation of the apparatus, as will become apparent, each of the tubes will be supported throughout most of its length by the stock from which the wall board is formed, and this supporting of the forming tubes is rendered particularly practicable for the reason that the lower portion of the board as viewed in Figure 2 possesses the necessary strength partly because of the quick drainage of water from the pulp and partly because of the 60 fact that the lower portion of the board is made up largely of long coarse fibers. The spiral grooves 106 are cut in such a direction with relation to the direction of rotation of the tube and with relation to the speed of rotation of the tube 65 as to tend to feed the pulp material horizontally 70 at a linear speed corresponding to that of the upper run 15 of the screen 16.

In addition to being wholly unsupported vertically from the bearings 113 to their free ends, 75 the tubes 105 are likewise obviously unsupported

against horizontal displacement. Means is provided to position the tubes horizontally without interfering with the continuous formation of the board. Referring to Figures 1, 2 and 4 the numeral 115 designates each of a plurality of spider structures each of which comprises a hub 116 having pairs of radial arms 117 the outer ends of which turn as at 118 away from the direction of rotation. In other words, each spider structure, as viewed in Figure 2, turns in a counterclockwise direction and the ends 118 are turned in a clockwise direction. The spaces between the arms 117 of each pair are approximately equal to the diameter of each tube 105 so as to receive one of these tubes therebetween. Moreover, the arms 117 are of such number and length that each successive pair of ends 118 will assume a position straddling its associated tube 105 before the preceding pair of ends 118 has moved above the associated tube 105. Thus there will always be at least one pair of arms 117 or their ends 118 in a position to prevent lateral displacement of each tube 105.

The hubs 116 are mounted on a transverse shaft 119 provided at one end with a pulley 120 adapted to be driven from any suitable source of power. The shaft 119 is driven preferably at such speed that the peripheral speed of the ends 118 will approximate the linear speed of the top run 15 of the wire 16. Of course, this linear speed of the ends 118 is circumferential and corresponds to the horizontal speed of the upper run 15 of the wire only at the instant when each end 118 is directly beneath the shaft 119. The difference in horizontal speed of the ends 118 at other points while they are in the body of the board does not affect the operation of the apparatus, however, and the depressions formed by the arms 117 and their ends 118 close as the board moves toward the right as viewed in Figure 2 due to the reasonably soft condition of the board at such point.

By the time the board has passed the right hand end of the deckel units as viewed in Figures 1 and 2 the board will have set sufficiently to be self supporting against sagging at the edges. Beyond the deckel the semi-formed board extends beneath the lower run 121 of a top wire 122 which may be identical in a conventional top wire of a Fourdrinier machine. This wire and its associated elements therefore need not be referred to in detail. The wire passes around end rolls 123 and 124 and thence over a top roll 125 and down toward the roll 123, over an intermediate roll 126. The roll 14 adjacent the roll 18 cooperates with a similar upper roll 127 to form a pair of squeeze rolls between which the wall board passes after moving a substantial distance between the upper and lower wires. These squeeze rolls definitely determine the final thickness of the board.

A section of the board is shown in Figure 9, the board being indicated as a whole by the numeral 128. The board when passing from the machine in substantially finished form will be cut in suitable lengths by any desired means and the finished individual boards will have openings 129 extending throughout the length of the board. While the finished board will not in fact show sharply defined layers there will be structural differences in various parts of the board through the thickness thereof. For example, in the lower portion 130 of the board as viewed in Figure 9, the board will be made up largely of large relatively coarse fibers while the central

portion 131 of the board through the thickness thereof will be made up largely of fibers of medium size. The top portion 132 of the board will be made up completely of relatively fine fibers which will permit the board to take a relatively flat smooth finish to adapt it for surface decorations of any desired type.

The openings 129 in the board serve several functions. In the first place, they increase the insulating value of the board materially, and in the second place, aside from their presence as dead air spaces, they provide for a much thicker board from the same amount of pulp stock. Additionally, the openings 129 serve to assist in fastening the wall board in position. For example, each opening 129 may have driven thereinto wood blocks 133 (Figure 10) which may be forced in by metal rods calibrated so as to permit the spacing of the blocks at desired intervals. These wood blocks may receive screws driven through the board from the outer side of the structure of which the board 128 is a part. For example, the board is shown in Figure 10, for the purpose of illustration, as lying against corrugated sheet metal 134 and a screw 135 is shown as being driven through the corrugated metal into the board at such a point as to engage one of the blocks 133. Thus it will be apparent that it is possible in some structures to secure the wall board firmly in position without driving fastening elements through the inner surface of the wall board.

The operation of the apparatus is as follows: The thin watery pulp is fed to the hopper 62, 35 as will be obvious, to be supplied to the screen 48. As previously stated this screen is preferably vibrated by rotation of the shaft 51 and eccentric 58, thus assisting in maintaining a uniform mixture of the fibers of the pulp in the 40 screen. Water is fed into the screen through the nozzle 63 and performs the same function as the eccentric mechanism in that it tends to stir and agitate the fibers. Both of the means referred to are preferably employed since it is desirable to keep the pulp in motion in the screen.

The openings 51 are of such size as to permit the passage therethrough of only the smallest fibers, and such fibers pass through the openings into the compartment 47. The openings 52 are of such size as to permit nothing larger than medium sized fibers, and accordingly fibers of such size and smaller will pass downwardly into the compartment 46. The largest fibers can pass through the openings 53 into the compartment 45 and since fibers of this size cannot pass through either the openings 51 or 52, all of the large fibers will find their way into the compartment 45.

The upper run of the screen 16 moves constantly toward the right as viewed in Figure 2 and this motion constantly withdraws material from the hoppers 45, 46 and 47, the material moving toward the right to make up the finished wall board as will become obvious. The separation of the fibers by the screen 50, acting as a classifier because of the difference in the sizes of the openings 51, 52 and 53, results in somewhat stratifying the fibers by the time they pass under the lower edge of the wall 41. It is not strictly true, of course, that definite stratification takes place since there will be a mixture of fine and medium sized fibers in the compartment 46 and a mixture of fibers of all sizes in the compartment 45. However, only the finest fibers 70 will be in the compartment 47 while all of the

coarse fibers will be in the compartment 45. There will be a graduation of the fibers through the thickness of the mass as it passes beneath the bottom of the wall 44, the finest fibers staying at the top of the mass as they pass from the compartment 47, the medium and fine fibers staying in the center of the mass from top to bottom as they pass from the compartment 46 and the coarsest fibers remaining at the bottom of the mass as they pass from the compartment 45.

As previously stated the pulp is fed to and through the screen 50 in a thin watery mass, a substantial amount of water being used to permit a constant thorough mixture of the fibers for the purpose of facilitating their partial classification as stated. Water in the mass between the walls 38 and 41 flows downwardly relatively readily and will pass through the top run 15 of the screen, the majority of the water being taken up by the suction boxes 28. While these boxes are shown as feeding water downwardly by gravity into the trough 31, it will be obvious that positive suction means may be connected to the pipes 29 in accordance with conventional practice.

As the mass passes beneath the lower edge of the wall 41 it will be apparent that the majority of water will have been drained from the mass although the latter is still in such a loose generally plastic condition as not to be self form-retaining. It is for this reason that the deckels 80 are provided. The mass will be prevented from spreading laterally on the top run 15 of the screen by proximity of the screen to each of the deckel screens 84 and each of these screens, backed up by the perforated belt 82, permits the passage of water from the edge portions of the screen. This operation facilitates and hastens the setting of the edge portions of the mass so as to render itself form-retaining by the time the mass passes beyond the deckels.

It will be apparent that the foregoing motion of the mass from the compartment 45, 46 and 47 takes place around the tubes 105. These tubes are spiralled as shown in Figures 2 and 5 with the spirals turning in the correct direction and at the correct pitch with relation to the direction and speed of rotation of each tube as to cause the spiral grooves to tend to move the mass at a linear speed corresponding to that of the upper run 15 of the screen. The relatively wet condition of the mass permits it to move freely with respect to the surface of each tube and the rotation of each tube prevents any adhesion of the mass thereto.

Thus the mass continues to move over the upper run 15 of the screen 16 with the tubes 105 embedded directly in the mass and as the material of the mass sets, openings will be formed therein corresponding in shape and size to the tubes 105. After leaving the deckels the mass will be only slightly thicker than the desired thickness of the resultant wall board and the mass passes beneath the bottom run 121 of the top wire 122. This wire tends to slightly compact the mass to assist in compressing water therefrom and the suction boxes 33 are provided to assist in taking from the mass as much water as possible prior to its exit from the machine. Before leaving the machine the board passes between the roll 14 adjacent the right hand end of the apparatus (Figure 2) and the roll 127, these rolls acting as squeeze rolls to reduce the mass to the final board thickness. The tubes 105 extend to

the limit of the outlet end of the apparatus and the board passing from the ends of the tube will retain the openings 129 (Figure 9) therein since at the outlet end of the apparatus the board will be wholly self form-retaining. Any suitable means may be employed for carrying off the continuously formed board and for periodically cutting the board transversely into individual pieces of the desired length.

As previously stated the tubes 105 are not provided with any positive supporting means from the bearings 113 (Figure 2) to the outlet end of the apparatus. When the apparatus is initially placed in operation suitable means may be employed, if desired, for initially supporting the free ends of the tubes 105. During the continuous operation of the apparatus, however, it will be obvious that the tubes will be in contact with the pulp material forming the bottom portion of the board and each tube is therefore in engagement with a supporting surface throughout its length. The ability of the material of the board to support the tubes is increased and rendered more positive by the fact that the bottom portion of the board is made predominately of the largest fibers in the mass. This fact renders the bottom of the board relatively structurally of substantial strength which is desirable in order to provide adequate support for the tubes 105. In addition, this structural strength improves the general quality of the board and renders it easier to permanently attach the resultant boards to a supporting surface or structure with less danger of any pulling out of the fastening elements occurring.

The bottom of the resultant board will be relatively rough but of substantial strength as stated, and such surface of the board is placed against the supporting surface or structure to which the individual boards are to be attached. The top surface of the board will be made up completely of the finest fibers in the mass, thus providing a top surface portion which is capable of being very smoothly surfaced, which is not possible with ordinary boards of this type wherein there is a relatively uniform distribution of fibers of different sizes with as many long coarse fibers forming one surface of the board as the other. The resultant board, therefore, possesses substantial inherent strength while at the same time providing a final surface with an extremely smooth texture particularly adapted for receiving surface coating or ornamentation of any desired type. The provision of the openings 129 improves the heat insulating value of the board by providing a thicker board for a given quantity of material per unit of size, and by providing dead air spaces in the board.

The use of the spiders 115 is not essential but is preferred. During the making of the board the tubes 105 are adequately supported by resting on the bottom portion of the mass from which the board is formed. This mass does not fixedly prevent lateral movement of the tubes 105, which is possible due to their resilience incident to their diameter in proportion to their length. On the other hand, there is less tendency for the tubes to move laterally since there is no force present tending to cause such movement as is true of vertical movement, the force of gravity tending to move the tube downwardly. To positively anchor the tubes in definite positions, however, the spiders 115 are preferably used and their operation was set forth above in connection with the description of their struc-

ture. The arms of the spider of each pair confine one of the tubes therebetween and a pair of spider arms are always in a position to positively prevent lateral movement of each tube.

It will be obvious that a number of the structural features of the apparatus have been only generally illustrated. For example, any suitable means may be employed, other than the means shown and described, for rotating the tubes 105 and the same is true of the specific means for driving the deckels. In connection with the latter elements it is particularly noted that the deckels of the present apparatus depart substantially from Fourdrinier practice in that they are much wider and are quite different in structure. Each deckel belt may be exactly vertically positioned by loosening the lock screw 70 of each deckel pulley and moving the pulley vertically on its associated shaft to exactly position the wire 84 of each deckel (Figure 8) so that its lower edge barely clears the adjacent upper surface of the edge portion of the top run 15 of the belt 16. With the mechanism so adjusted the flanges 81 at the bottoms of the deckel pulleys will adequately carry the load of the deckel, while the flanges 81 will be arranged beneath the edge of the adjacent edge of the screen 16 to clear this screen and accordingly avoid any wear thereon. Each deckel may be suitably tightened by adjustment of the screw 17 (Figure 7) as will be obvious.

As previously stated the elements 105 are tubular and are perforated as at 107. While it is not essential, it will be apparent that these tubes are of substantial value for purposes other than those described in that they may be used as means for injecting into the board any desired fluid for any desired purpose. For example, air may be blown through the tubes and out through the perforations 107 to positively prevent any adhesion of the mass to the tubes, or any desired gases or chemicals may be forced through the tubes and through the openings 107 to effect a strengthening of the resultant board, or for any other purpose.

The resultant board may be freely used whenever a wall board of this general type has been previously employed, but with improved results. The board possesses substantial structural strength to permit it to be permanently attached wherever desired, and the board possesses a high degree of heat insulating value. As suggested in Figure 10 wood blocks 133 may be forced into the openings 129 to remain therein at spaced intervals to serve as means for more positively securing the wall boards in position. For example, the wall board may be secured directly against a corrugated metal structure 134 and screws 135 may be passed through the metal structure to engage in the wood blocks 133, thus fastening the boards in position from the outside and completely eliminating any marks on the inner surface of the board incident to the use of fastening elements commonly employed.

From the foregoing it will be apparent that the present invention contemplates a method of making wall board from fibrous material wherein there is a relative separation of the fibers and a subsequent bringing together of the fibers in a predetermined relatively stratified relationship whereby one surface of the resultant board will be made up of relatively coarse interlocked fibers to present a wall board of increased strength. The method also contemplates the placing together of the fibers in such relationship that the

other surface of the board will be made up solely of fine fibers so as to permit the making of a resultant board having one very smooth face particularly adapted for receiving surface coatings, 5 ornaments or the like. Moreover, the present method contemplates the continuous formation of wall board material by the feeding of fibrous material in such a manner that forming elements remain wholly within the limits of the 10 mass while the board is being formed, thus providing a resultant board having openings therethrough. In accordance with such feature of the method a resultant board of a given width and length may be made substantially thicker with 15 the same amount of material and the resultant board will possess heat insulating characteristics superior to previous wall board structures because of such increased thickness and because of the formation of the openings parallel to the surfaces 20 of the board.

While I have described in detail the preferred practice of my process and a preferred form of apparatus with which it is to be used, it is to be understood that the form of apparatus and the 25 details of procedure of the process may be widely varied without departing from the spirit of the invention or the scope of the subjoined claims.

I claim:

1. The method of making relatively thick wall 30 board or the like from a thin watery fiber-containing mix which sets by the removal of liquid therefrom, which comprises moving a mass of the mix in a given direction with an elongated forming element submerged therein and extending 35 in such direction and fixed against longitudinal movement, and progressively removing liquid from the mass to cause the mass to set during its travel in said direction until it is self form-retaining when it leaves said forming element, 40 whereby the resultant board will be provided with an opening extending therethrough corresponding in shape and size to the cross-sectional shape and size of the forming element.

2. The method of making relatively thick wall 45 board or the like from a thin watery fiber-containing mix which sets by the removal of liquid therefrom, which comprises moving a mass of the mix in a given direction with an elongated forming element submerged therein and extending in 50 such direction and fixed against longitudinal movement, progressively removing liquid from the mass to cause the mass to set during its travel in said direction until it is self form-retaining when it leaves said forming element, whereby the 55 resultant board will be provided with an opening extending therethrough corresponding in shape and size to the cross-sectional shape and size of the forming element, and continuously rotating said forming element to assist in preventing adhesion thereto of the material on said screen.

3. The method of making relatively thick wall 60 board or the like from a thin watery fiber-containing mix which sets by the removal of liquid therefrom, which comprises moving a mass of the mix in a given direction with an elongated forming element submerged therein and extending in 65 such direction and fixed against longitudinal movement, progressively removing liquid from the mass to cause the mass to set during its travel in said direction until it is self form-retaining when it leaves said forming element, whereby the 70 resultant board will be provided with an opening extending therethrough corresponding in shape and size to the cross-sectional shape and size of the forming element, and feeding a fluid to the 75

surfaces of the openings formed by the forming element during the movement of the mass with respect thereto, by pumping the fluid through the forming element.

4. The method of forming relatively thick wall board or the like from a thin watery fiber-containing mix which sets by the removal of liquid therefrom, which comprises subjecting a mass of the mix to a separating action to at least partially separate the mass according to sizes of the fibers therein, continuously feeding the respective mass-separations one behind another to a moving horizontal screen to superimpose them whereby the resultant board will have the portion adjacent one face thereof made up of fine fibers of the original mass and the portion adjacent the opposite face thereof made up predominantly of the coarse fibers of the original mass and whereby the liquid content of the mass will be progressively reduced by drainage of the liquid through the screen, and maintaining within the moving mass a forming element fixed against longitudinal movement and elongated in the direction of travel of the mass on the screen and of such length that the mass will have become self form-retaining before leaving the forming element, whereby the resultant board will be formed with an opening extending longitudinally therethrough corresponding in cross-sectional shape and size to the cross-sectional shape and size of the forming element.

5. An apparatus for forming relatively thick wall board or the like comprising a longitudinally movable horizontal supporting screen, means for supplying to one end of said screen a relatively thin watery mass of fiber-containing mix, parallel means projecting upwardly from opposite edges of said screen to maintain the mix thereon to a substantial depth until it becomes self form-retaining, a forming element projecting longitudinally of the screen and supported throughout the greater portion of its length by the material thereon whereby the material moves continuously from the end of said forming element, said forming element being of such length that the material on the screen will be self form-retaining as it moves from said forming element to leave a resultant opening longitudinally throughout the resultant board, means for rotating said forming element to assist in preventing adhesion thereto of the material on said screen, said forming element being circular in cross-section and being provided with a spiral groove of such pitch with relation to the speed and direction of turning movement of the forming element as to tend to move the material on the screen at the speed of movement of the screen.

6. An apparatus for forming relatively thick wall board or the like comprising a longitudinally movable horizontal supporting screen, means for supplying to one end of said screen a relatively thin watery mass of fiber-containing mix, parallel means projecting upwardly from opposite edges of said screen to maintain the mix thereon to a substantial depth until it becomes self form-retaining, a forming element projecting longitudinally of the screen and supported throughout the greater portion of its length by the material thereon whereby the material moves continuously from the end of said forming element, said forming element being of such length that the material on the screen will be self form-retaining as it moves from said forming element to leave a resultant opening longitudinally throughout the resultant board, said forming element

being of tubular form and having radial openings for the passage from the interior of the tube of a fluid pumped into one end of the forming element.

5 7. Apparatus for forming relatively thick wall board or the like comprising a longitudinally movable horizontal screen, means for supplying a relatively thin watery fiber-containing mix to said screen, a forming tube above and parallel to the screen and extending in the direction of travel thereof, means for supporting one end of said tube adjacent said end of said screen, said tube being supported throughout the greater portion of its length by the material on the screen 10 whereby the latter is movable freely from the other end of the tube in the form of a board having an opening therethrough formed by said tube, and means for rotating said tube.

8. Apparatus for forming relatively thick wall board or the like comprising a longitudinally movable horizontal screen, means for supplying a relatively thin watery fiber-containing mix to said screen, a forming element extending over the wire in spaced relation thereto and extending in 15 the direction of travel thereof, said forming element being positively supported solely adjacent said end of the screen and supported throughout the greater portion of its length by the material on the screen to form a resultant board 20 having an opening extending therethrough, and means for rotating said tube, said tube being provided with a spiral groove of such pitch with relation to the speed and direction of rotation of the tube as to tend to move the material on the 25 screen in the direction and at the speed of movement thereof.

9. Apparatus for forming relatively thick wall board or the like from a thin watery fiber-containing mix which sets by the removal of liquid 30 therefrom, comprising a longitudinally movable horizontal supporting screen, means for progressively supplying the mix to one end of said screen whereby the mix travels with the screen and liquid drains from the mix through said screen, parallel means projecting upwardly from opposite 35 edges of said screen to maintain the mix thereon to a substantial depth until it sets, a forming element projecting longitudinally of the screen and fixed against longitudinal movement, and means for supporting said forming element 40 adjacent said end of said screen, the other end of said forming element projecting through the mix to be supported solely by the mix as the latter progressively sets, said forming element 45 being of such length that the material on the screen will be self form-retaining as it continuously moves from the last named end of said forming element to leave a resultant opening longitudinally through the resultant board.

10. Apparatus for forming relatively thick wall board or the like from a thin watery fiber-containing mix which sets by the removal of liquid therefrom, comprising a longitudinally movable horizontal supporting screen, means for progressively supplying the mix to one end of said screen whereby the mix travels with the screen and liquid drains from the mix through said screen, parallel means projecting upwardly from opposite edges of said screen to maintain the mix thereon to a substantial depth until it sets, a forming element projecting longitudinally of the screen and fixed against longitudinal movement, means for supporting said forming element adjacent said end of said screen, the other end of 55 said forming element projecting through the mix

to be supported solely by the mix as the latter progressively sets, said forming element being of such length that the material on the screen will be self form-retaining as it continuously moves from the last named end of said forming element to leave a resultant opening longitudinally through the resultant board, and means for rotating said forming element to assist in preventing adhesion thereto of the material on said screen.

11. Apparatus for forming relatively thick wall board or the like from a thin watery fiber-containing mix which sets by the removal of liquid therefrom, comprising a longitudinally movable horizontal screen, means for progressively supplying the mix to said screen adjacent one end thereof, and a forming element extending over the screen in spaced relation thereto in the direction of travel thereof and fixed against movement in such direction, said forming element being supported solely adjacent said end of the screen and being of such length to require support adjacent its other end in order to retain it in spaced relation throughout its length to said screen, said screen serving to drain liquid from the mix thereon so that the mix becomes self supporting before reaching the last named end of said forming element to form a resultant board

having an opening extending therethrough and to serve as a support for the last named end of said forming element.

12. Apparatus for forming relatively thick wall board or the like from a thin watery fiber-containing mix which sets by the removal of liquid therefrom, comprising a longitudinally movable horizontal screen, means for progressively supplying the mix to said screen adjacent one end thereof, a forming element extending over the screen in spaced relation thereto in the direction of travel thereof and fixed against movement in such direction, said forming element being supported solely adjacent said end of the screen and being of such length to require support adjacent its other end in order to retain it in spaced relation throughout its length to said screen, said screen serving to drain liquid from the mix thereon so that the mix becomes self supporting before reaching the last named end of said forming element to form a resultant board having an opening extending therethrough and to serve as a support for the last named end of said forming element, and means for continuously rotating said forming element to assist in preventing adhesion thereto of the material on said screen.

WILLIAM G. BRUBACHER.
